UNITED STATES PATENT OFFICE

128,136

DESIGN FOR AN ELECTRIC SWITCH

Norman C. Fetter, Freeport, Ill., assignor to
Micro Switch Corporation, Freeport, Ill., a cor-
poration of Illinois

Application August 3, 1940, Serial No. 94,170

Term of patent 14 years

To all whom it may concern:

Be it known that I, Norman C. Fetter, a citizen
of the United States, residing at Freeport, in
the county of Stephenson and State of Illinois,
have invented a new, original, and ornamental
Design for an Electric Switch, of which the fol-
lowing is a specification, reference being had to
the accompanying drawing, forming part thereof,
and in which:

Fig. 1 is a perspective view of an electric switch
showing my new design;

Fig. 2 is a side elevational view of the same
switch;

Fig. 3 is a bottom plan view thereof; and
Figs. 4 and 5 are end elevational views thereof.

I claim:

The ornamental design for an electric switch,
as shown.

NORMAN C. FETTER.
